Primary Examiner — Kevin Rudzinski(74) *Attorney, Agent, or Firm* — General Counsel PC(57) **CLAIM**

The ornamental design for a hookah, as shown and described.

DESCRIPTION

FIG. 1 is a front perspective view of the hookah from an angle of about 22.5 degrees from the front of the hookah;

FIG. 2 is a front view of the hookah in elevation;

FIG. 3 is a rear view of the hookah in elevation;

FIG. 4 is a side view of the hookah in elevation;

FIG. 5 is the opposite side view of the hookah in elevation of that depicted in FIG. 4;

FIG. 6 is a top view of the hookah; and,

FIG. 7 is a bottom view of the hookah.

The broken lines shown in the drawings illustrate portions of the hookah and environmental features that form no part of the claimed design.
